SHOULDER FIREARM HAVING SEPARATE PROJECTILE AND POWDER MAGAZINES

Edwin R. Michelson, Berkeley, Mo.

Application June 7, 1954, Serial No. 434,929

7 Claims. (Cl. 42—17)

This invention relates in general to certain new and useful improvements in firearms and, more particularly, to a sportsman's gun which can be readily adapted for various types of hunting needs.

At the present time, the average sportsman needs a variety of different guns for different types of shooting. It is usual practice to employ a gun of small caliber in hunting light game since a large caliber high-velocity missile would damage the game. On the other hand, for very large animals, it is essential to use a gun of large caliber in order to make a kill. The average hunter will, therefore, find it necessary to invest in a number of different guns involving a very substantial expense, both in the weapons themselves and in the purchase of various different types of ammunition required by them. Actually, the caliber of the gun is less important than the size of the powder charge used as a propellant for the bullet or missile. This latter factor determines muzzle velocity, which, in turn, is the most significant factor in the striking power of the missile. For this reason, manufacturers of ammunition supply cartridges having different powder charges and this variant complicates, rather than simplifies, the problem of the hunter in meeting all the needs of the sport.

It is, therefore, the primary object of the present invention to provide a gun capable of firing a projectile with a primer in its base and using loose powder as a propellant, thereby obviating the need for ejecting spent cartridge shells.

It is also an object of the present invention to provide a gun of the type stated in which the quantity of propellant used can be varied to afford different muzzle velocity and killing power.

It is a further object of the present invention to provide a gun of the type stated in which the projectile and propellant are automatically fed into the chamber in proper relation for firing.

It is another object of the present invention to provide a gun of the type stated which is relatively light in weight due to the fact that the stresses absorbed by the breech bolt in firing are not transmitted to the receiver, thus obviating the need for a massive highly stressed receiver.

It is another object of the present invention to provide a gun of the type stated which is relatively economical in cost of manufacture due to the utilization of a simple cam and cam-like principle for locking of the breech bolt.

It is a further object of the present invention to provide a gun of the type stated which is economical in use by reason of the fact that the ammunition employed therein can be manufactured economically and at low cost.

It is another object of this invention to provide a gun which has a mechanism capable of generating a high pressure between the breech bolt and its seat, thus obviating the need of a cartridge case for sealing purposes.

It is another object of this invention to provide a gun

2

which can be atmospherically sealed, if necessary, due to the absence of ejection ports.

With the above and other objects in view, my invention resides in the novel features of form, construction, arrangement, and combination of parts presently described and pointed out in the claims.

In the drawings—

Figure 1 is a side elevational view of a gun constructed in accordance with and embodying the present invention;

Figure 2 is a perspective view of the gun barrel with various portions of the mechanism removed in order to illustrate more clearly the spatial relationship of the various components;

Figure 3 is a front elevational view of the gun;

Figure 4 is a fragmentary sectional view of the gun taken along line 4—4 of Figure 3, showing the action of the gun in loaded and cocked position ready for firing.

Figure 5 is a fragmentary sectional view substantially similar to Figure 4, showing the position of the action of the gun after the gun has been fired;

Figure 6 is a fragmentary sectional view substantially similar to Figure 4, showing the action of the gun as the fore-end is shifted to unlocked position in the course of reloading and cocking;

Figure 7 is a fragmentary sectional view substantially similar to Figure 4, showing the action of the gun at the instant of initial engagement with the powder-feeding mechanism during reloading;

Figure 8 is a fragmentary sectional view substantially similar to Figure 4, showing the action of the gun at the instant of initial engagement with the bullet-magazine release during reloading;

Figure 9 is a fragmentary sectional view substantially similar to Figure 4, showing the action of the gun as the fore-end has been shifted to rearwardmost position;

Figures 10, 11, 12, and 13 are transverse sectional views taken along lines 10—10, 11—11, 12—12, and 13—13, respectively, of Figure 4;

Figure 14 is a fragmentary sectional view taken along line 14—14 of Figure 4 and showing the bolt and firing pin mechanism in cocked position ready for firing;

Figure 15 is a fragmentary sectional view substantially similar to Figure 14, showing the positions of the bolt at instant of firing and immediately thereafter;

Figure 16 is a fragmentary sectional view substantially similar to Figure 14, showing the position of the bolt after firing action has been completed;

Figure 17 is a fragmentary sectional view substantially similar to Figure 14, showing the position of the gun bolt when the fore-end is in rearwardmost position as the gun is being reloaded and cocked;

Figure 18 is a transverse sectional view taken along line 18—18 of Figure 1;

Figure 19 is a schematic fragmentary perspective view of the firing-lock actuator;

Figures 20, 21, and 22 are fragmentary sectional views taken along lines 20—20, 21—21, and 22—22, respectively, of Figure 14;

Figure 23 is a fragmentary sectional view taken along line 23—23 of Figure 20;

Figures 24 and 25 are fragmentary sectional views taken along lines 24—24 and 25—25, respectively, of Figure 21;

Figure 26 is a fragmentary sectional view taken along line 26—26 of Figure 12;

Figure 27 is a fragmentary sectional view taken along line 27—27 of Figure 4;

Figure 28 is a schematic perspective view of the powder-feeding piston and related structure;

Figure 29 is a fragmentary sectional view taken along line 29—29 of Figure 28;

Figure 30 is a fragmentary sectional view taken along line 30—30 of Figure 29;

Figure 31 is a fragmentary sectional view taken along line 31—31 of Figure 12; and

Figure 32 is a fragmentary sectional view taken along line 32—32 of Figure 31.

Referring now in more detail and by reference characters to the drawings, which illustrates a preferred embodiment of the present invention, A designates a gun comprising a barrel 1 forged or otherwise suitably formed from gun steel and integrally including a muzzle portion 2, an intermediate portion 3, and a chamber portion 4, and a relatively long breech portion 5. As will be seen by reference to Figure 2, the muzzle portion 2 is tubular and at its rearward end tapers into the intermediate portion 3, and is eccentric with relation thereto and is provided with two laterally projecting longitudinal ribs 6 for slidably receiving a wooden fore-end 7. At its rearward end, the intermediate portion 3 merges into the chamber portion 4 which is substantially rectilinear in cross-sectional shape and is also tangent along its upper surface to the upper surfaces of the muzzle portion 2 and intermediate portion 3 so that a smooth, uninterrupted line of sight for aiming purposes is thereby afforded down the gun barrel between the rear sight 8 and front sight 9. It will be understood in this connection that the muzzle portion 2, the intermediate portion 3 and chamber portion 4 are provided with a common coaxial bore 10 which extends rearwardly from the muzzle portion 2 through the intermediate portion 3 and into the chamber portion 4 being therein diametrically enlarged along a taper 11 to form a chamber 12, which in turn extends rearwardly through the remainder of the chamber portion 4 and terminates in a very slight rearwardly tapered shoulder or annular seat 13. Extending rearwardly from the shoulder 13 in coaxial alignment with the bore 10 and chamber 12 is a breech-bore 14 which extends longitudinally through the breech portion 5 and terminates in a short diametrically enlarged internally threaded section 15 adapted for receiving a flat externally threaded closure plug 16. Formed integrally with and extending rearwardly from the breech portion 5 are two spaced parallel ears 17, 18, respectively having aligned apertures 19, 20. The aperture 20 is somewhat smaller than the aperture 19 and is internally threaded for receiving the threaded end of a stock-retaining screw 21 having an enlarged head 22 for snug-fitting seated disposition within the aperture 19. Provided for snug-fitting retentive engagement between the ears 17, 18 is a wooden gun stock 23 apertured at its forward end for receiving the screw 21 and being provided on its under face with a scoop-shaped indentation 24, as best seen in Figures 1 and 5 and for purposes presently more fully appearing.

The opposite vertical side walls of the breech portion 5 are provided with elongated breech-bolt slots 25 which are transversely aligned and are of such length and location that the forward ends thereof are spaced rearwardly of the shoulder 13. Adjacent their rearward ends the side walls of the breech portion 5 are provided with laterally opening rectangular recesses 26 having flush fitting closure plates 27 secured snugly thereacross by means of short screws 28 and thereby providing a completely enclosed elongated slide-chamber 29 which opens to the interior of the breech-bore 14 through elongated slots 30. The under side of the forwardly presented end face of the chamber portion 4 is provided with an arcuate transversely extending recess 31 and the chamber portion 4 and breech portion 5 are longitudinally drilled just inwardly of their lateral faces to provide two parallel tubular bores 32 opening at their opposite ends respectively into the chambers 29 and recess 31 for slidably accommodating elongated locking rods 33.

The bore 10 is of substantially uniform internal diam-

etral size and is provided with internal rifling grooves 34 rearwardly for most of its entire length. However, a short distance forwardly from the chamber 12, the bore 10 is diametrically enlarged very slightly along an almost imperceptible taper for a distance substantially equal to the body portion of the bullet or projectile B which is designed for use with the gun A, as will be presently more fully discussed. This slightly enlarged unrifled or bullet seating portion of the bore 10 is intended to retain the bullet B snugly when the gun is loaded and ready for firing and thereby provide a forward seal for the chamber 12 so that the energy developed at the instant of detonation will be efficiently converted into propelling force impinging upon the rearwardly presented end of the bullet B and imparting thereto the required forward velocity. It will be noted that the bullet does not include any jacket or shell containing a powder charge but is merely provided in its rearwardly presented end with a centrally disposed impact-firing detonating cap 35.

The top wall of the breech portion 5 directly to the rear of the shoulder 13 is provided with a clear out aperture 36 having a hinged cover plate 37 which is spring biased downwardly into closed position and is conventionally mounted on a hinge block 38. On its under face the breech portion 5 is provided with an elongated arcuate recess 39 for rigidly receiving a longitudinally extending tubular powder magazine 40 which is internally threaded adjacent its rearward end, as at 41, for receiving a removable filling plug 42. Slidably mounted within the powder magazine 40 is a powder-feeding piston 43 is operatively engaged around the forward end of a spring 44, which is, in turn, abuttingly fitted at its rearward end against the interior face of the plug 42. At its forward end, the powder magazine 40 is cut off obliquely and opens into a rearwardly and downwardly extending tubular powder-feeding cylinder 45 which extends upwardly and is rigidly mounted at an oblique angle in the lower forward part of the breech portion 5 in such a manner as to open into the breech-bore 14 rearwardly of the shoulder 13. The powder magazine 40 and powder-feeding cylinder 45 are preferably, though not necessarily, of the same diametral size. At its lower end, the powder-feeding cylinder 45 is internally threaded for receiving a suitably threaded closure plug 46 having an inwardly presented interior face 47. Operatively mounted within the cylinder 45 is an open-bottomed hollow powder-feeding piston 48 having an upwardly presented arcuately dished end face 49 adapted to conform to a section of the interior surface of the breech-bore 14. The rearwardly presented side face of the powder-feeding piston 48 is diametrically indented for 180° around its periphery to provide a semi-circular space 50 for slidably accommodating a hemi-cylindrical gate 51. At their lower ends, adjacent the axial line or margin therebetween, the gate 51 and piston 48 are rigidly provided with radially outwardly projecting pins 52, 53, adapted for slidable disposition within diametrically opposed axially extending slots 54 formed in the side walls of the powder-feeding cylinder 45 and opening at their lower ends to the bottom margin of the powder-feeding cylinder 45, so that, when the closure plug 46 is removed, the piston 48, gate 51, and associated structure may be inserted into the cylinder 45 from the bottom. At their outer ends, the pins 52 and 53 are welded or otherwise rigidly mounted adjacent the bottom portions of companion-shaped flat slide plates 55, 56, respectively, the latter being, in turn, provided adjacent their upper ends with outwardly projecting pins 57, 58, respectively. As will be seen by reference to Figure 29, the pins 57, 58, are parallel to each other and to the center line of the pins 52, 53. Furthermore, the flat plates 55, 56, are contoured to fit snugly against the outer face of the powder-feeding cylinder 45 in overlying relation to the slots 54 and are operatively confined for slidably movement between ways 59, 59', 60, 60', respectively, as best seen in Figures 2 and 18.

The rearwardly presented face of the piston 48 is provided with an elongated slot 61 which is positioned centrally of, and underlies, the gate 51 for slidably accommodating a tongue 62 which projects radially into the hollow interior of the powder-feeding piston 48 and bears against an elongated compression spring 63 which extends lengthwise downwardly through the powder-feeding cylinder 45 and abuts at its lower end against the inner face of the closure plug 46. Also operatively mounted within the powder-feeding cylinder 45 in forwardly spaced parallel relation to the spring 63 is a second spring 64 which bears at its upper end against the under face of the top wall of the powder-feeding piston 48 and at its lower end against the inner face of the closure plug 46. Rigidly mounted at its lower end centrally within the closure plug 46 and extending axially upwardly through the powder-feeding cylinder 45 is a rod 65 which terminates at its upper end below the lowest point of movement of the tongue 62 so as to avoid any interference therewith. This rod 65 functions as a separating element between the two springs 63, 64, so that the latter will function independently and will not interfere with each other.

Rigidly joined to the downwardly presented inclined face of the powder-feeding cylinder 45 and forming a part thereof is a substantially smaller tubular bullet-magazine 66 also mounted at its upper end, at an oblique angle, in the breech portion 45 and opening into the breech-bore 14 between the powder-feeding cylinder 45 and the shoulder 13. At its lower end, the bullet-magazine 66 is internally threaded for receiving a closure plug 67. Operatively mounted within the bullet-magazine 66 is an elongated compression spring 68 which bears at its opposite ends respectively against the inner face of the closure plug 67 and the downwardly presented end face of the lowermost bullet B. As will be evident from a consideration of Figure 4, the spring 68 urges the bullets upwardly toward the chamber 12. Welded or otherwise suitably mounted upon the outer face of the bullet-magazine 66 adjacent its upper end is a pivot block 69 having downwardly presented spaced parallel ears 70 for receiving a pivot pin 71. Rockably mounted upon the pivot 71 is a bifurcated arm 72 which is operatively engaged with the downwardly projecting end of a bullet-retention pin 73 shiftably mounted in and extending through the upper end of the pivot block 69 and projecting at its inner end into the upper end of the bullet-magazine 66 for engagement with the upper end of the uppermost bullet B, as best seen in Figure 4. The pin 73 is biased toward inwardly disposed or bullet-engaging position by means of a tension spring 74. Also pivotally mounted on the pin 71 between the lower ends of the bifurcated arm 72 is an actuating arm 75 having relatively wide laterally projecting ears 76. The arm 75 is integrally provided with an upwardly extending finger 77 which normally bears against a stop pin 78 rigidly mounted in the bifurcated arm 72, the arm 75 being resiliently held in such position by means of a tension spring 79. Thus, when the actuating arm 75 is swung rearwardly in the direction indicated by the arrow in Figure 26, the bifurcated arm 72 will be swung outwardly away from the pivot block 69 and the pin 73 will be retracted to permit a bullet B to be fed upwardly into the chamber 12. On the other hand, when the pin 73 and bifurcated arm 72 return to normal position, as shown in Figure 26, the lower end of the actuating arm 75 is free to swing forwardly (i. e. to the right in Figure 26) without affecting the position of the pin 73 and bifurcated arm 72. It will be noted, by reference to Figure 26, that the pivot block 69 is provided with a semi-circular milled slot 80 merely to afford clearance for the upper end of the finger 77 of the actuating arm 75.

Slidably mounted within the breech-bore 14 is a tubular breech-bolt 81 which is diametrically turned at its forward end to form a short tapered shoulder 82 adapted

for tight-fitting seated engagement against the shoulder or annular seat 13. Forwardly of the shoulder 82, the breech-bolt 81 is internally counter-bored to provide a scavenging skirt 83 having a series of narrow axial slots 84, so that the outer peripheral margin 85 of the skirt 83 will at all times be in resilient scraping engagement with the inner surface of the chamber 12. Formed integrally with, and projecting axially forwardly from, the breech-bolt 81, is a tapered bullet-feeding finger 86 having four thin arcuate wings 87 arranged at ninety-degree intervals therearound for picking up and propelling the bullet B into firing position without contacting the detonating cap 35. Directly to the rear of the scavenging skirt 83, the breech-bolt 81 is provided with a solid body section 88, which, in common with the finger 86, is axially bored for slidably accommodating a firing pin 89 having a pointed end 90 for contacting the detonating cap 35 and being integrally provided on its rearward end with a diametrically enlarged button-like head 91. Interposed between the head 91 and the rearwardly presented face of the body section 88 is a light compression spring 92 for normally biasing the firing pin 89 into the rearward position shown in Figure 14.

Rearwardly of the body section 88, the breech-bolt 81 is internally bored to provide a hammer chamber 93 provided adjacent its rearward end with an inwardly projecting narrow annular flange 94. The hammer chamber 93 is furthermore provided at its bottom with an axial slot 95 for clearing a cocking lug 95' held in place by screws s, as shown in Figure 22. The breech-portion 5 is drilled and tapped in upwardly spaced alignment with the cocking lug 95' for receiving a threaded plug p to facilitate installation of the cocking lug 95'. At points ninety degrees upwardly on either side of the center line 35 of the slot 95, the hammer chamber 93 is provided on its interior wall with detent notches 96. Slidably mounted within the hammer chamber 93 is a tubular hammer 97 provided in its forwardly presented end face with a concentric circular recess 98 for loosely engaging the head 91 of the firing pin 89. On its rearwardly presented face, the hammer 97 is provided with an annular concentric recess 99 and an integrally formed rearwardly extending axial bolt pin 100 having an integrally formed annular collar 101 and a diametrically enlarged cylindrical head 102. Slidably mounted within the hammer chamber 93 and also extending loosely and slidably around the bolt pin 100 is a compressor 103 provided in its forwardly presented end face with a cylindrical recess 104 having substantially the same diametral size as the largest diametral dimension of the recess 99. Operatively mounted within the recesses 99 and 104 and extending co-axially around the bolt pin 100 is a relatively strong firing spring 105. The compressor 103 is provided in its rearwardly presented face with a pair of 55 diametrically opposite slot-like recesses 106 for pivotally accommodating latch-dogs 107 which are biased to the position shown in Figure 14 by springs 108 for engagement in the detent notches 96. The latch-dogs 107 are provided at their inner ends with rearwardly presented abutment shoulders 109 positioned for operative engagement with the collar 101 of the bolt pin 100, as will presently be more fully explained. Interposed between the head 102 of the bolt pin 100 and the internal annular flange 94 of the breech-portion 81 is a conical retraction spring 110. It should be noted in this connection that the firing spring 105 is much stronger than the retraction spring 110 and the two springs will thus perform their respective functions without interference with each other.

At about thirty degrees arcuately around, and downwardly from, the plane of the latch-dogs 107, the hammer 97 is provided with a diametral recess 111 having a reduced end portion 112 for housing a light-weight compression spring 113 which bears against a pin-like sear 114 having an end face 115 conforming to the outer curvilinear surface of the hammer chamber 93. The

end face 115 of the sear 114 bears against a supplementary sear-pin 114', which is, in effect, a longitudinal extension of the sear 114 and is provided at its outer end with a slot 116 having a diametral pin 117 for camming engagement with an inclined slot formed in a blade-like sear-actuating section 118 milled in a trigger pin 119 which is shiftably mounted in, and extends longitudinally through, a suitable bore 120 formed in the interior of the breech-portion 5, as shown in Figure 25. At its rearward end, the trigger pin 119 is provided with rock-toothed sections 121 for meshing engagement with the toothed segment 122 of a trigger-actuating arm 123 rigidly pinned to a trigger pintle 124, which is, in turn, rotatably mounted in, and projects laterally outwardly from, the breech-portion 5. Disposed within the forward end of the bore 120 and bearing against the forward end of the trigger pin 119 is a compression spring 125 for biasing the trigger pin rearwardly. At its outer end, the trigger pintle 123 is rigidly pinned to one portion of a two-part split trigger yoke 126. The other portion of the trigger yoke 126 is pivotally mounted at its upper end upon a stud 127 also mounted in, and projecting outwardly from, the breech-portion 5 in axial alignment with the trigger pintle 124. The two parts of the trigger yoke 126 are held together in assembled relation by a fastening screw 128 to form a depending trigger 129, all as best seen in Figure 13.

The rectangular recesses 26 are provided with front and rear end walls 130, 131, and with flat back walls 132 which are spaced inwardly from and parallel to the closure plates 27. Slidably mounted within each recess 26 is a block 133 rigidly fixed, as by means of a set-screw 134, to the rear end of the locking rods 33. Extending transversely across the breech-bore 14 is a cross-bar 135 having rod-like arms 136 and a central flattened section 137 adapted for abutment against the rear face of the head 102 of the bolt-pin 100. At its opposite ends, the cross-bar 135 extends loosely through the slots 30 and is rigidly fastened by means of set-screws 138 in the upper ends of the blocks 133, all as best seen in Figure 19. Disposed endwise between the rear face of the flattened section 137 of the cross-bar 135 and the opposed interior face 139 of the closure plug 16 is a compression spring 140 for biasing the locking rods 33 forwardly.

The body portion 83 of the breech-bolt 81 is provided in its lateral faces with shallow recesses 141 having centrally located drilled and tapped holes 142. Set snugly, but removably, within each of the recesses 141 and projecting laterally outwardly therefrom through the breech slots 25 are breech-bolt studs 143 having flattened top and bottom faces for slide forming disposition within the breech slots 25. In this connection, it may be pointed out that the breech-bolt studs 143 are relatively wide in the direction of the slots 25 in order to provide sufficient strength to hold the breech-bolt 81 seated against the shoulder 13 when the powder-charge is exploded within the chamber 12. The force involved at the instant of explosion is of the order of 50,000 p. s. i. Rotatably mounted on the projecting ends of the breech-bolt studs 143 are spacing washers 144, bolt-actuating slide-plates 145, and cap-washers 146 all held securely in place by retainer bolts 147, as best seen in Figure 14.

The slide-plates 145 extend angularly downwardly and forwardly along the opposite side faces of the chamber portion 4 and at their forward ends are cross-connected by a lock-bar 148 rotatably set at its ends in the slide-plates 145 and having a rearwardly presented semi-circular face 149 shaped for snug-fitting disposition within the transverse semi-circular recess 31 and having a pair of rearwardly presented drill-holes 33' for receiving the locking rods 33 when the gun is cocked and ready to fire. Thus, it is impossible to work the gun action again until the gun has been fired. Rigidly attached to the lock-bar 148 is a forwardly extending intermediate link

150 pivotally connected at its forward end to a pair of main actuating links 151, which are, in turn, pivotally connected to the fore-end 7. The intermediate link 150 is provided with laterally projecting stop-pins 152 for engaging the actuating links 151 when the fore-end is slid rearwardly and the links 150, 151, are brought into the relative angular position shown in Figure 6. Similarly, the slide-plates 145 are provided with stop-pins 153 for engaging the intermediate link 150 when the links 150, 151, and slide-plates 145 are brought into the relative angular position shown in Figure 7. In this latter position, the links 150, 151, the slide-plates 145, and breech-bolt 81 will slide rearwardly as a unit to the rearwardmost position shown in Figure 17.

15 The slide-plates 145 are provided upon their inner faces with inwardly projecting co-axial pins 154 for engaging and tripping the finger 77 during the course of rearward travel of the slide-plates 145, as shown in Figure 26. Finally, the slide-plates 145 are also provided upon their inner faces with inwardly projecting pins 155 for rockably supporting gauge-plates 156 which extend angularly downwardly in the position shown in Figure 31 and at their lower ends are provided with outwardly projecting studs 157, which, in turn, extend through arcuate slots 158 formed in the slide-plates 145. At their outer ends the studs 157 are threaded and provided with shouldered cap-nuts 159 for tightly securing the gauge-plates 156 in any adjusted position within the limits of the slots 158. The outwardly presented lateral faces of the slide-plates 145 may, if desired, be inscribed with a suitable scale to facilitate adjustment of the gauge-plate 156 for reasons presently more fully appearing.

Rockably mounted at the lower end of each gauge-plate 156 and extending facewise upwardly therealong, as shown in Figure 31, is a camming bar 160 for actuating engagement with the pins 57, 58, of the powder-feeding piston 48. The camming-bars 160 are held against forward swinging relative movement by pins 161 set into the gauge-plates 156, and are biased into contact therewith by leaf-springs 162. As will be seen by reference to Figures 7 and 8, the camming-bars 160 will ride against the pins 57, 58, forcing the gate 51 downwardly. As will be seen by reference to Figure 30, the spring 64 is heavier than the spring 63 and will normally hold the latter compressed under the finger 62. Thus, the gate 51 and piston 48 will maintain the relative positions shown in Figure 30 and the downward movement of the gate 51 will be transmitted through the finger 62 and compressed spring 63 to the piston 48. Consequently, the gate 51 and piston 48 will momentarily come to rest in the position shown in Figure 30 and a charge of powder will be pushed from the powder magazine 40 by the piston 43 into the powder-feeding cylinder 45 on top of the piston 48. However, as the slide-plates 145 continue to move to rearwardmost position, the camming-bars 160 will also move backwardly, thereupon riding past the said pins 57, 58, permitting them and the elements associated therewith to return to initial position. This movement allows the gate 51 to snap up to initial position under the force of the spring 63 transmitted through the tongue 62, cutting off the powder intake from the magazine 40, but the powder charge momentarily holds the piston 48 back until the bolt 81 reaches fully retracted position, at which moment the piston 48 propels the powder charge into the chamber 12. As the slide-plates 145 subsequently return forwardly to initial position, as shown in Figure 4, the upwardly and forwardly presented faces of the camming-bars 160 will strike against the pins 57, 58, and be swung rearwardly against the bias of the leaf-springs 162, thereby clearing and passing under the pins 57, 58. Similarly, the pins 154 will clear and pass under the finger 7.

The lock-bar 148 is provided in its semi-circular face with recesses 33' for snug-fitting engagement with the forward ends of the locking rods 33, as best seen in Figure

2, thereby locking the gun A in the cocked position shown in Figure 4 and preventing manipulation of the fore-end 7 and movement of the slide-plates 145 until the gun A has been fired. The hammer 97 and other internal elements of the breech-bolt 81 are in position, as shown in Figure 14, when the gun A is cocked and ready to fire.

Mounted at their rear ends upon the breech-bolt studs 143 and held inwardly by means of the washers 144 are leaf-spring closure-blades 164 adapted to cover forward portion of the slots 25 when the bolt 81 is retracted, thereby preventing loose powder from spilling out accidentally. The closure-blades 164 are slidably supported within U-shaped elements 165 formed integrally upon the chamber portion 4 for holding the closure-blades 164 snugly against the side faces thereof.

Assuming that the chamber 12 is filled with a charge of powder, a bullet B is in firing position and the breech bolt 81 is in fully cocked position as shown in Figure 14, the gun A is fired by squeezing the trigger 129, whereupon the trigger actuating rod 119 slides forward camming the sear 114 inwardly until its end face 115 is coincident with the interior face of the breech-bolt chamber 93. Thereupon, the spring 105 throws the hammer 97 forward against the head 91 of the firing pin 89, which, in turn, is driven sharply forward against the detonating cap 35 of the bullet B, exploding the powder charge in the chamber 12 and propelling the bullet B out through the muzzle of the gun A. During this movement, the compressor 103 is held stationary with respect to the breech bolt 81 by engagement of the latch-dogs 107 in the detent notches 96, as shown in Figure 14, and the hammer will have moved from the position shown in Figure 14 all the way forward and will have come to rest against the button-like head 91 of the firing pin 89, which will, in turn, have come to rest in its forwardmost position. In this position, the spring 105 is fully relaxed.

As the hammer 97 shifts forwardly, it pulls the bolt pin 100 forwardly compressing the spring 110, and as the hammer 97 reaches its forwardmost position just after the moment of firing, the collar 101 strikes against the abutment surfaces 109 of the latch-dogs 107, releasing them. The stored energy in the spring 110 thereupon pulls the bolt pin 100 rearwardly, pulling the compressor 103 and hammer 97 to be returned as a unit through the position shown in Figure 15 to the position shown in Figure 16. Since the spring 105 is now relaxed, it will not interfere with this return movement. The rear end 102 of the bolt-pin will strike against the cross-bar 136 moving the latter backwardly from the position shown in Figure 15 to the position shown in Figure 16, since the spring 110 is much stronger than the spring 140. This movement will shift the locking rods 33 rearwardly out of the drill holes 33', unlocking the lock-bar 148.

The fore-end 7 can then be shifted rearwardly to the position shown in Figures 9 and 17 and in so doing the bullet retention pin 73 is tripped and the piston 48 and gate 51 are actuated, whereby a bullet is taken from the magazine 66 and a powder charge from the powder-feeding cylinder 45. As has been previously pointed out, the pins 154 trip and pass under the finger 77, so that the spring 74 can return the retention pin 73 to initial position immediately after the uppermost bullet in the magazine 66 has been shifted up into the chamber 12. Thus, only one bullet at a time can be fed out of the magazine 66. As the breech-bolt 81 moves into rearward position, the cocking lug 95' engages the compressor 103 and holds it stationary while the rest of the action moves rearwardly. As soon as the sear 114 moves into line with the aperture in which it is normally seated, it will re-engage and lock the hammer 97 to the breech-bolt 81. Thereupon, continued rearward movement of the breech-bolt 81 will cock the compressor.

The fore-end 7 is then returned to initial position carrying the cocked bolt 81 up to firing position as shown in Figure 14, and the lock-bar 148 will roll into the recess 31. In this position, the cross-bar 136 is released so that the locking rods 33 will return forwardly to locking position. As the fore-end 7 returns to such initial position, it will kick the forward ends of the locking rods 33 back momentarily until fully seated, whereupon the locking rods 33 will shift forwardly again to locked position in the recesses 33'.

By adjusting the gauge-plate 156 up and down, the degree of sliding movement of the piston 48 and gate 51 can be varied to vary the size of the powder charge injected into the magazine 40.

It should be understood that changes and modifications in the form, construction, arrangement, and combination of the several parts of the firearms may be made and substituted for those herein shown and described without departing from the nature and principle of my invention.

Having thus described my invention, what I claim and desire to secure by Letters Patent is:

1. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a bolt slidably mounted at the rear end of and in axial alignment with the chamber and having an annular shoulder for engagement against the seat, actuating means for shifting the bolt to-and-fro into and out of seated position, a projectile magazine located below the chamber and rearwardly of the throat in downwardly and angularly projecting relation thereto, spring-biased means in the projectile magazine for injecting a single projectile at a time from the projectile magazine into the chamber, means on the forward end of the bolt for seating said projectile in said throat, a powder magazine located below the chamber and rearwardly of the projectile magazine in parallel relation to the chamber, a powder-feeding cylinder mounted at the rear of and parallel to the projectile magazine, said cylinder being in communication at its upper end with the powder magazine, a spring-biased piston in the powder magazine for injecting a charge of powder from the powder magazine into the powder-feeding cylinder, and piston-like means in the powder-feeding cylinder for introducing said charge of powder into the chamber.

2. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a bolt slidably mounted at the rear end of and in axial alignment with the chamber and having an annular shoulder for engagement against the seat, actuating means for shifting the bolt to-and-fro into and out of seated position, a projectile magazine, spring-biased means in said projectile magazine, means associated with the projectile magazine and operated by the actuating means as the bolt is retracted from seated position, said last-named means being located below the chamber and projecting externally of the projectile magazine.

for releasing and thereby permitting the spring-biased means to inject a single projectile at a time from the projectile magazine into the chamber, means on the forward end of the bolt for seating said projectile in said throat, a powder magazine located below the chamber and rearwardly of the projectile magazine in parallel relation to the chamber, a powder-feeding cylinder mounted at the rear of and parallel to the projectile magazine, said cylinder being in communication at its upper end with the powder magazine, a spring-biased piston in the powder magazine, means operable responsive to movement of the actuating means for injecting a charge of powder from the powder magazine, and piston-like means in the powder-feeding cylinder operable responsive to movement of the actuating means as the bolt is retracted from seated position for introducing said charge of powder into the chamber.

3. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a bolt slidably mounted at the rear end of and in axial alignment with the chamber and having an annular shoulder for engagement against the seat, actuating means for shifting the bolt to-and-fro into and out of seated position, a projectile magazine located below the chamber and rearwardly of the throat in downwardly projecting relation thereto, spring-biased means in said projectile magazine, means associated with the projectile magazine and operated by the actuating means as the bolt is retracted from seated position, said last-named means being located below the chamber and projecting externally of the projectile magazine for releasing and thereby permitting the spring-biased means to inject a single projectile at a time from the projectile magazine into the chamber, means on the forward end of the bolt for seating said projectile in said throat, a powder magazine located below the chamber and rearwardly of the projectile magazine in parallel relation to the chamber, a powder-feeding cylinder mounted at the rear of and parallel to the projectile magazine, said cylinder being in communication at its upper end with the powder magazine, a spring-biased piston in the powder magazine for injecting a charge of powder from the powder magazine, and piston-like means in the powder-feeding cylinder operable responsive to movement of the actuating means as the bolt is retracted from seated position for introducing said charge of powder into the chamber.

4. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a bolt slidably mounted at the rear end of and in axial alignment with the chamber and having an annular shoulder for engagement against the seat, actuating means for shifting the bolt to-and-fro into and out of seated position, a projectile magazine located below the chamber and rearwardly of the throat in downwardly and angularly projecting relation thereto, spring-biased means in the projectile magazine for injecting a single projectile at a time from the projectile magazine into the chamber, means on the forward end of the bolt for seating the

projectile in said throat, a powder magazine located below the chamber and rearwardly of the projectile magazine in parallel relation to the chamber, a powder-feeding cylinder mounted at the rear of and parallel to the projectile magazine, said cylinder being in communication at its upper end with the powder magazine, a spring-biased piston in the powder magazine, means operable responsive to movement of the actuating means for injecting a charge of powder from the powder magazine, and piston-like means in the powder-feeding cylinder operable responsive to movement of the actuating means as the bolt is retracted from seated position for introducing said charge of powder into the chamber.

5. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a bolt slidably mounted at the rear end of and in axial alignment with the chamber and having an annular shoulder for engagement against the seat, actuating means for shifting the bolt to-and-fro into and out of seated position, a projectile magazine, spring-biased means in said projectile magazine, means associated with the projectile magazine and operated by the actuating means as the bolt is retracted from seated position, said last-named means being located below the chamber and projecting externally of the projectile magazine for releasing and thereby permitting the spring-biased means to inject a single projectile at a time from the projectile magazine into the chamber, means on the forward end of the bolt for seating said projectile in said throat, a powder magazine located below the chamber and rearwardly of the projectile magazine, in parallel relation to the chamber, a powder-feeding cylinder mounted at the rear of and parallel to the projectile magazine, said cylinder being in communication at its upper end with the powder magazine, a spring-biased piston in the powder magazine for injecting a charge of powder from the powder magazine, piston-like means in the powder-feeding cylinder operable responsive to movement of the actuating means as the bolt is retracted from seated position for introducing said charge of powder into the chamber, and a locking pin for engaging the actuating means as the latter is returned to initial position for preventing further movement thereof until the gun has been fired.

6. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, an annular seat in said chamber located rearwardly of the throat, the distance between the throat and the seat being sufficient to provide space for receiving a powder charge, a hollow bolt slidably mounted at the rear end of and in axial alignment with the chamber and having an annular shoulder for engagement against the seat, actuating means for shifting the bolt to-and-fro into and out of seated position, a projectile magazine located below the chamber, spring-biased means in said projectile magazine, means associated with the projectile magazine and operated by the actuating means as the bolt is retracted from seated position, said last-named means being located below the chamber and projecting externally of the projectile magazine for releasing and thereby permitting the

spring-biased means to inject a single projectile at a time from the projectile magazine into the chamber, means on the forward end of the bolt for seating said projectile in said throat, a powder magazine located below the chamber and rearwardly of the projectile magazine in parallel relation to the chamber, a powder-feeding cylinder mounted at the rear of and parallel to the projectile magazine, said cylinder being in communication at its upper end with the powder magazine, a spring-biased piston in the powder magazine actuated by the actuating means as the bolt is retracted from seated position for injecting a charge of powder from the powder magazine into the powder-feeding cylinder, and piston-like means in the powder-feeding cylinder for introducing said charge of powder into chamber.

7. A gun adapted for firing a cartridge-less projectile having a detonating cap in its base, said gun comprising a chamber, a barrel extending forwardly from the chamber and having a rifled bore throughout its length except for a section adjacent to the chamber, said barrel being diametrically enlarged and smooth-surfaced in said section to provide a projectile-engaging throat into which the projectile may be snugly seated prior to firing, a breech portion extending rearwardly from the chamber and having side walls provided with opposed parallel slots, a bolt slidably mounted in the chamber and breech por-

tion for longitudinally shiftable movement therein, said bolt having laterally projecting bosses slidably mounted in and extending through the slots, a fore-end operatively mounted on the barrel for forward and rearward sliding movement, actuating links pivotally connected at their forward ends to the fore-end, intermediate links pivotally connected at their forward ends to the actuating links, a pair of slide plates pivotally connected at their rear ends respectively to said bosses and at their forward ends to the rear end of the intermediate links, camming-bar means operatively mounted on the actuating links for locking engagement with the barrel when the fore-end is in forwardly shifted position, means operable responsive to forward movement of the fore-end for seating a projectile in said throat, and means operable responsive to rearward movement of the fore-end for introducing a charge of powder into the chamber.

UNITED STATES PATENT OFFICE
CERTIFICATE OF CORRECTION

July 8, 1958

Patent No. 2,841,906

Edwin R. Michelsen

It is hereby certified that error appears in the above numbered patent requiring correction and that the said Letters Patent should read as corrected below.

In the grant, lines 1 and 12, name of inventor, for "Edwin R. Michelson", each occurrence, read -- Edwin R. Michelsen --; in the heading to the drawings, Sheets 1 to 6, line 1, for "E. R. Michelson", each occurrence, read -- E. R. Michelsen --; at the bottom of the drawings, Sheets 1 to 6, and in the heading to the printed specification, line 4, for "Edwin R. Michelson, each occurrence, read -- Edwin R. Michelsen --.

Signed and sealed this 18th day of November 1958.
